United States Patent Office

Des. 205,208
Patented July 5, 1966

205,208

UTILITY TRACTOR

Sherman C. Heth and Evan T. Lewis, Racine, Wis., assignors to Jacobsen Manufacturing Company, Racine, Wis., a corporation of Wisconsin

Filed May 19, 1965, Ser. No. 85,351

Term of patent 14 years

(Cl. D14—3)

FIG. 2

FIG. 3

FIG. 1 is a right-side perspective view of our design for a utility tractor. The side opposite is the same as the side shown.

FIG. 2 is a top plan view of FIG. 1.

FIG. 3 is a rear elevation view of FIG. 1.

We claim:

The ornamental design for a utility tractor, substantially as shown and described.
